H. S. Bailey.

Attorney.

UNITED STATES PATENT OFFICE.

WILLIS A. McCLELLAND, OF DENVER, COLORADO.

ILLUMINATED WREATH.

Application filed December 11, 1923. Serial No. 679,997.

To all whom it may concern:

Be it known I, WILLIS A. McCLELLAND, a citizen of the United States of America, residing at the city and county of Denver ⁵ and State of Colorado, have invented a new and useful Illuminated Wreath, of which the following is a specification.

This invention relates to improvements in illuminated wreaths for decorative purposes.

The object of the invention is to provide a wreath which may be made up of twigs, or branches of any suitable variety of tree, or of a suitable plant, such as Lycopodium, ¹⁵ which may be dyed so as to retain a fresh green appearance, the said wreath being provided with illuminating means.

Further, to provide a wreath of suitable material, having a flat ring-like back of ²⁰ wood or of pasteboard, upon which is mounted a plurality of incandescent lamp sockets, which may be electrically connected in either series or parallel, as may be desired, said sockets being either miniature, candelabra, ²⁵ or standard base, and being fitted with lamps of a single color or of a variety of colors, which project forward through the wreath, the feed wires for the lamps being of ample length, and being provided with the usual ³⁰ style of plug for connection with an electric light socket.

These objects are accomplished by the character of wreath illustrated in the accompanying drawings, in which:

Figure 1 is a front view of a wreath constructed in accordance with my invention.

Fig. 2 is a front view of the ring-like backing to which the wreath is secured, and showing lamp sockets thereon, which are ⁴⁰ electrically connected in series.

Fig. 3 is a view in diagram and on a smaller scale, of the ring shown in Figure 2, and showing the lamp sockets connected in parallel. And

Fig. 4 is a sectional view—full size—of one of the lamp sockets.

Referring to the accompanying drawings:

The numeral 1 indicates a flat ring-like member, of any desired diameter, which may be made of pasteboard or of wood, or of any other suitable light material, and which forms the backing for the wreath. Upon this ring are secured a plurality of equidistant incandescent lamp sockets, eight of ⁵⁵ such sockets being shown in the drawings. Each socket comprises a circular base 2 of

non-conducting material, such as porcelain, which is secured to the ring by screws, as shown, and which is provided with a socket member 3, in which is fitted the usual threaded shell 4, in which is screwed the plug portion of the lamp. The shell 4 is formed with a terminal strip 5, which projects laterally from its lower end and which extends out through an opening 6 in the socket member, and a binding screw 7 passes through this terminal and enters a threaded hole in the base 2.

A non-conducting washer 8 is seated in the bottom of the shell 4, and rests upon ⁷⁰ an inwardly projecting flange of the said shell, and a screw 9 passes through the washer 8 and through a hole in the base and into a threaded hole in a terminal strip 10, which is seated in a recess in the base, the ⁷⁵ outer end portion of said strip passing up through an opening in the base and resting upon the base, as clearly shown in Figure 4. A binding screw 11 passes through a hole in the terminal strip 10 and into a threaded ⁸⁰ hole in the base 2, and the recess in the base, in which the strip is seated, is filled with a suitable cement 12 to prevent contact with the ends of the screws 9 and 11 and with the terminal strip 10. Thus the ⁸⁵ screw 9 forms a contact for one of the lamp terminals, and the shell 4 a contact for the other lamp terminal, as will be understood. When the lamp sockets are arranged in series, as shown in Figure 2, a conductor ⁹⁰ wire 13 extends from the terminal 5 of the first socket of the group, to the terminal 10 of the second socket, and on from one socket to the next succeeding socket in this manner, until the last socket is reached. A feed ⁹⁵ wire 14 is connected to the terminal 5 of the last socket, and extends through a hole 15 in the ring 1, and a feed wire 16 is connected with the terminal 10 of the first socket, and also passes through the hole 15 ¹⁰⁰ in the ring 1, and these feed wires may be of any required length, and their free ends are connected in the usual manner to a common form of plug 17 for connection with an ordinary lamp socket.

When connecting the sockets in parallel, as shown in the diagram, Figure 3, a wire 18 is connected to the terminal 5 of the first socket of the group and to the terminal 5 of each succeeding socket until the last ¹¹⁰ socket is reached, and from the terminal 5 of the last socket the wire is passed

- through the hole 15 in the ring 1, as shown. A wire 19 is then connected to all of the terminals 10 of the sockets, beginning with the first socket, and from the terminal 10 5 of the last socket the wire 19 is passed through the hole 15 in the ring, and the free ends of these wires are connected to a lamp socket plug, as described in connection with the wires 14 and 16 of Figure 2.
- 10 The wires are connected to the terminal strips 10 by the binding screws 11, and to the terminal strips 5, by the binding screws 7. Eight lamps are preferably employed when they are to be connected in series; but 15 when they are connected in parallel, any desired number may be employed, but in connection with a transformer. The lamps may be of any type, and of a single color or of a variety of colors.
- 20 The wreath proper 20, is preferably made of sprigs of some tree or plant of the evergreen variety, and preferably of a variety of plant known as Lycopodium, such varieties being appropriate to the Christmas 25 season, when wreaths are in general demand, and when the latter variety of plant is employed, it is preferably dyed green in order that the freshness of color may be retained for an indefinite period. In forming the wreath, sprigs of this plant are arranged in close overlapping order upon the ring 1, so as to entirely conceal the ring, and to form an unbroken circle, which shall have a uniform appearance throughout; 30 the stem portions being securely fastened to the ring in any suitable manner. In connection with the wreath, I employ an artificial representation of a suitable flower 35 21, preferably the flower of shrub known as poinsettia, which is a popular Christmas 40

flower, and these flowers are arranged at regular intervals and so as not to hide the lamps. I have shown three of these flowers on the wreath illustrated in Figure 1, but any desired number may be employed. 45

A wreath of the character described makes a beautiful and appropriate Christmas decoration, and is particularly effective when placed in windows. In practice, the wreath is hung at any desired point, and the plug 50 17 at the end of the feed wires is screwed into a nearby lamp socket, whereby electric current may be supplied to the lamps illuminating the wreath, by night.

A wreath of this character is not only 55 attractive in appearance by day, but it also possesses the added attraction of an illuminated wreath by night.

Having described my invention, what I claim as new and desire to secure by Letters 60 Patent, is:

1. A wreath of the character described, having a flat, stiff, non-conducting ring-like backing, lamp sockets on said backing, wires connecting said lamps in circuit, and feed 65 wires connected to said lamp circuit wires, and adapted to be connected with an electric current source.

2. A wreath comprising a flat annular backing of non-conducting material, lamp 70 sockets mounted on the backing and electrically interconnected, and floral material secured upon the backing forming the wreath.

In testimony whereof I affix my signature 75 in presence of two witnesses.

WILLIS A. McCLELLAND..
